UNITED STATES PATENT OFFICE.

CHARLES W. MORGAN, OF MILWAUKEE, WISCONSIN, ASSIGNOR, BY DIRECT AND MESNE ASSIGNMENTS, TO GASOLINE TURBINE MOTOR COMPANY, OF RACINE, WISCONSIN.

ROTARY GAS-ENGINE.

1,113,234.

Specification of Letters Patent.

Patented Oct. 13, 1914.

Application filed December 4, 1913. Serial No. 804,585.

To all whom it may concern:

Be it known that I, CHARLES W. MORGAN, a citizen of the United States, and resident of Milwaukee, in the county of Milwaukee and State of Wisconsin, have invented certain new and useful Improvements in Rotary Gas-Engines; and I do hereby declare that the following is a full, clear, and exact description thereof.

10 The object of my invention is to provide a simple, economical and highly efficient valveless gas engine of the rotary type, the construction and arrangement being such that in the cycle a volume of gas is introduced successively into a series of gas pockets of a rotor and is thereafter compressed followed by ignition coincident to registration of a pocket with a combustion chamber that is formed in a shell about the rotor, 15 whereby power is applied to said rotor through force exerted upon a shiftable piston that is carried by the same. The cycle is completed by the combustion piston traveling beyond the field of the firing chamber, 20 which chamber is provided with an open end in communication with an exhaust port formed in the shell, it being understood that previous to the introduction of the fuel charge within a gas pocket a partial vacuum 25 is formed therein in conjunction with the pocket being brought into registration with a receiving chamber that is also formed in the aforesaid shell. The arrangement and construction also contemplates the embodiment 30 of a suction and compression piston, which piston is adapted to travel in the receiving chamber and effect the desired suction and compression operations.

With the above objects in view the invention consists in certain peculiarities of construction and combination of parts as hereinafter set forth with reference to the accompanying drawings and subsequently claimed.

45 In the drawings Figure 1 represents a sectional elevation of an engine embodying the features of my invention; Fig. 2, a cross-section of the same, the section being indicated by line 2—2 of Fig. 1; Fig. 3, a similar 50 cross-section, the same being taken upon a plane as indicated by line 3—3 of Fig. 1, and Fig. 4, a detailed cross-section as indicated by line 4—4 of Fig. 1.

Referring by characters to the drawings, 55 1 represents a water-cooled cylindrical shell

provided with an integral cap 2, and a removable cap 3. The shell is cut away circumferentially through a portion of its circumference to form an exhaust port 4, which port communicates with the open end of a combustion chamber 5 that is formed within the inner circular wall of said shell, extending a predetermined distance from the exhaust port and at its closed end 5' the said combustion chamber merges into the circular shell wall, through the medium of a gentle curve or slope. At a slight distance from the closed end 5' of the combustion chamber the inner circular wall of the shell recedes in a gradual curve to form one end 60 of a circular receiving chamber 6, the opposite end of said chamber being similarly curved upward to the general circular wall of the shell, whereby a solid circular cut-off face 7 is formed between the juxtaposed end 65 of the receiving chamber and the exhaust port 4. As shown by the drawings, the receiving chamber 6 is of much greater area 70 than the combustion chamber.

The caps 2 and 3 of the shell are provided 80 with centrally disposed hubs for the reception of a shaft 8, which shaft has fixedly secured thereto a rotor 9. The removable cap 3 of the shell is provided with an inwardly projecting centrally disposed hollow head 85 10, the bore of which is of sufficient diameter to form an air chamber 10' about the hub portion 9' of the rotor, which hub portion projects into the head and abuts the adjacent cap 3, as shown, the said cap being provided 90 with vent apertures 10'' that communicate with the air chamber. The head 10 is cut away radially to form an air passage 10''', as best shown in Fig. 1, and the exterior face 95 of the head is also recessed to form a gas chamber 11, which gas chamber is closed by the annular wall of a circular recess 9'' that is formed in the rotor, the said wall, together with the head, being slightly tapered 100 to form a ground joint fit. A volatile gaseous fluid is supplied to the gas chamber by means of a pipe 12, it being understood that the fuel is preferably carbureted air, but, in some instances, kerosene or other gaseous fluids may be utilized as a substitute 105 therefor.

The rotor is provided with two or more gas pockets 13 which extend from the periphery of said rotor to the circular recess 9'' therein, it being understood that the 110

rotor is arranged to travel in the direction as indicated by the arrow. Pivotaly mounted in each gas pocket, or in immediate advance thereof, is a combustion piston 14, the free end of which piston is adapted to impinge against the bottom wall of the combustion chamber, being thrown in such position by centrifugal force. Outward movement of each combustion piston 14 is limited by an offset shoulder portion which is adapted to abut a corresponding shoulder portion of the rotor that is formed about the oscillatory seat of said piston. Directly rearward of each gas pocket the rotor is tangentially slotted for the reception of a reciprocative receiving piston 15. These pistons extend flush with the sides of the rotor, whereby their side edges form steam-tight joints in connection with the shell caps, which joints are packed by suitable spring-controlled strips 16 having anchor-dowels for holding the same in position. Each receiving piston 15 may also, as shown, be provided with coiled springs 17, which coiled springs are seated within sockets formed in the rotor below the piston, whereby said pistons are pressed outwardly, it being understood, however, that, in some instances, the springs may be dispensed with, under which conditions the centrifugal force will serve to throw the same outwardly to their working positions. The shell 1 is also provided with an aperture 1' that communicates with the combustion chamber adjacent to its closed end, the said aperture being for the purpose of receiving a spark-plug 18. This plug carries an insulated conductor having one or more exposed spring terminals 19, which terminals are arranged to be engaged by metallic ends of the combustion pistons, whereby ignition is effected, it being understood that the electric current for supplying the spark is grounded through the rotor.

In order to insure a perfectly tight joint between the combustion piston and the bottom wall of the combustion chamber, each piston may, as shown, be provided with a spring-pressed metallic packing strip 14', which packing strip will thus be yieldingly pressed against the opposing face of the aforesaid combustion chamber. In order to prevent premature sparking each of the combustion pistons has embedded therein a strip of fiber 14" or other non-conducting material, which strips are alined with the contact spring terminals 19, the same being adapted to travel thereover and effect closure of the circuit co-incident to their engagement with the free end of the piston.

As shown in Fig. 1 of the drawings, a gas pocket is in communication with the closed end of the combustion chamber, the said gas pocket containing a charge of compressed gaseous fluid. Owing to the fact

that the rotor is in motion the combustion piston in advance of the pocket has entered the combustion chamber and cut off communication between the pocket and the open end thereof. Hence, as the piston travels past the igniter terminals 19, a spark is produced, whereby explosion takes place within the pocket and combustion chamber. The expanding gases exerting pressure upon the piston 14 will cause the rotor to travel in the direction of the arrow under the applied force. When the combustion piston passes the open end of the combustion chamber, communication is established between said open end and the exhaust port 4. Hence the spent gases will be expelled to atmosphere and, owing to the rapid movement of the rotor, fresh air will be sucked through the vent holes into the air chamber 10 and from thence said fresh air will be expelled through the gas pocket to thus thoroughly scavenge the same, it being understood that the inner end or mouth of the gas pocket at this time has established communication between the air chamber and exhaust port through the air passage 10''. Co-incident to cleansing of the gas pocket the reciprocative receiving piston 15, which is related to the preceding pocket and rearward thereof, has entered the receiving chamber 6 and, in its travel therein, created a vacuum rearward of said preceding piston. The oncoming empty gas pocket previously mentioned will now, after passing the cut-off face 7, establish communication between that portion of the receiving chamber containing a partial vacuum and, co-incident to establishing this communication, the inner or mouth end of the pocket traveling about the head 10 will establish communication with the gas chamber 11 in said head, whereby a charge of carbureted air will be drawn into the pocket and receiving chamber, to thus balance the partial vacuum previously effected, it being understood that the receiving piston in advance of the pocket in the meantime is creating a suction to thoroughly fill the chamber and pocket with the desired quantity of gas. After this has been effected, the inner end of the pocket 13 is cut off from the gas chamber and its companion receiving piston will now start to compress the charge to the desired volume preparatory to being fired, it being understood that when this compression takes place that the receiving piston in advance which had produced the suction stroke has passed beyond the end of the receiving chamber. Thus the cycle is completed.

From the foregoing it is apparent that each receiving piston performs a double function, that is, while compressing a charge of gas in advance it is simultaneously creating a vacuum rearwardly for the introduc-

tion of another charge of gas. It will also be understood that the receiving pistons when not in operation will ride upon the edge walls of the combustion chamber and 5 exhaust port 4 and will thus be held against radial throw-out until such time as they reach the receiving chamber, the side walls of which are flush with the shell caps 2 and 3.

While I have shown and described an engine provided with three sets of gas pockets and related mechanism, it is apparent that 10 two of such sets or a greater number may be utilized without departing from the spirit of my invention. It is also within the scope of 15 my invention to arrange several shells and rotors upon a single shaft for increasing the efficiency of the motor. Furthermore it should be understood that, while I have shown and described one exemplification of 20 my invention minutely as to details of construction, I may, without departing from the spirit of my invention, vary any or all of such details within the skill of the mechanic.

Attention is also called to the fact that the 25 combustion pistons 14 are provided with tail-pieces 15' in order to effect a partial balance of pressure incidental to a gas explosion whereby undue friction is eliminated in connection with the joint between these pistons 30 and the bottom wall of the combustion chamber.

I claim:

1. A rotary gas engine comprising a cylindrical shell having a receiving chamber and a 35 combustion chamber separated from each other and formed in its interior circular wall, the shell being provided with an exhaust port in communication with one end of the combustion chamber, a rotor mounted in the 40 shell adapted to close the ends of the receiving chamber and the firing end of the combustion chamber, the rotor being provided with peripheral gas pockets, a shiftable combustion piston carried by said rotor 45 in advance of each gas pocket, a shiftable receiving piston carried by said rotor rearwardly of each gas pocket, a vented centrally disposed head provided with a gas

chamber carried by the shell, the same being arranged to successively establish communication from its vented portion to the exhaust port through the gas pocket and from its gas chamber through the gas pocket to the receiving chamber. 50

2. A rotary gas engine comprising a cylindrical shell provided with a gas receiving chamber and a combustion chamber separated from each other, the combustion chamber being of comparatively small area and having one end in communication with the 55 atmosphere, a rotor having radially disposed pockets extending therethrough, a head carried by the shell adapted to control the inner ends of the pockets, the head being provided with an air chamber having a passage therethrough and a gas chamber in its periphery, a shiftable combustion piston carried by the 60 rotor in advance of each pocket, and a shiftable receiving piston carried by said rotor 65 rearwardly of each pocket. 70

3. A rotary engine comprising a shell provided with inner circular walls having an exhaust port therethrough, a combustion chamber formed in the circular wall in communication with the exhaust port and a receiving chamber formed in the circular wall spaced from the exhaust port and combustion chamber, a fixed head carried by the shell having a vented air chamber in communication with the exterior face of said head, 75 and a gas chamber formed in the exterior walls of said head, a rotor having a circular face mounted within the shell, the rotor being provided with radial gas pockets extending from its periphery to the head, and a 80 pair of shiftable pistons carried by the rotor 85 upon opposite sides of the peripheral mouth of each gas pocket.

In testimony that I claim the foregoing I have hereunto set my hand at Milwaukee in 90 the county of Milwaukee and State of Wisconsin in the presence of two witnesses.
